(57) **CLAIM**

I claim the ornamental design for an full-dip overshoe, as shown and described.

DESCRIPTION

FIG. 1 is a top view of a full-dip overshoe according to a new design.

FIG. 2 is a right side view of the full-dip overshoe shown in FIG. 1.

FIG. 3 is a bottom view of the full-dip overshoe shown in FIG. 1.

FIG. 4 is a perspective view of the full-dip overshoe shown in FIG. 1.

FIG. 5 is a top view of a second embodiment of a full-dip overshoe according to a new design.

FIG. 6 is a right side view of the full-dip overshoe shown in FIG. 5.

FIG. 7 is a bottom view of the full-dip overshoe shown in FIG. 5.

FIG. 8 is a perspective view of the full-dip overshoe shown in FIG. 5.

FIG. 9 is a top view of a third embodiment of a full-dip overshoe according to a new design.

FIG. 10 is a right side view of the full-dip overshoe shown in FIG. 9.

FIG. 11 is a bottom view of the full-dip overshoe shown in FIG. 9.

FIG. 12 is a perspective view of the full-dip overshoe shown in FIG. 9.

FIG. 13 is a top view of a fourth embodiment of a full-dip overshoe according to a new design.

FIG. 14 is a right side view of the full-dip overshoe shown in FIG. 13.

FIG. 15 is a bottom view of the full-dip overshoe shown in FIG. 13.

FIG. 16 is a perspective view of the full-dip overshoe shown in FIG. 13.

FIG. 17 is a top view of a fifth embodiment of a full-dip overshoe according to a new design.

FIG. 18 is a right side view of the full-dip overshoe shown in FIG. 17.

FIG. 19 is a bottom view of the full-dip overshoe shown in FIG. 17.

(Continued)

FIG. 20 is a perspective view of the full-dip overshoe shown in FIG. 17.
 FIG. 21 is a top view of a sixth embodiment of a full-dip overshoe according to a new design.
 FIG. 22 is a right side view of the full-dip overshoe shown in FIG. 21.
 FIG. 23 is a bottom view of the full-dip overshoe shown in FIG. 21.
 FIG. 24 is a perspective view of the full-dip overshoe shown in FIG. 21.
 FIG. 25 is a top view of a seventh embodiment of a full-dip overshoe according to a new design.
 FIG. 26 is a right side view of the full-dip overshoe shown in FIG. 25.
 FIG. 27 is a bottom view of the full-dip overshoe shown in FIG. 25.
 FIG. 28 is a perspective view of the full-dip overshoe shown in FIG. 25.
 FIG. 29 is a top view of an eighth embodiment of a full-dip overshoe according to a new design.
 FIG. 30 is a right side view of the full-dip overshoe shown in FIG. 29.
 FIG. 31 is a bottom view of the full-dip overshoe shown in FIG. 29; and,
 FIG. 32 is a perspective view of the full-dip overshoe shown in FIG. 29.
 Features shown in broken lines in the drawings are not part of the claim.
